UNITED STATES PATENT OFFICE.

GEORGE CROMPTON, JR., OF WORCESTER, MASSACHUSETTS, ASSIGNOR TO ROBERT G. PRATT, OF WORCESTER, MASSACHUSETTS.

SHUTTLE-CHANGING MECHANISM FOR LOOMS.

Application filed October 3, 1921. Serial No. 504,869.

To all whom it may concern:

Be it known that I, GEORGE CROMPTON, Jr., a citizen of the United States, residing at Worcester, in the county of Worcester and Commonwealth of Massachusetts, have invented a new and useful Improvement in Shuttle-Changing Mechanism for Looms, of which the following, together with the accompanying drawings, is a specification.

10 My invention relates to shuttle changing mechanism for looms, particularly of the so-called "narrow ware" type in which a plurality of spaced shuttles are adapted to be driven back and forth in unison with respect to a plurality of spaced groups of warp threads in order to simultaneously weave a number of separate strips of narrow fabric, such for example, as tape or ribbon.

In most of the looms of this type, as heretofore constructed, it is necessary for a loom operator to stop the loom every time it is necessary to change a shuttle or quill, following the exhaustion of the filling therein, and since such changes have to be made at frequent intervals, they cause considerable loss of time, with consequent reduction in the output of the loom. I am aware that it has been heretofore proposed to provide shuttle changing mechanism for looms of this type whereby it is possible for the operator to change a shuttle without interrupting the operation of the loom, but in so far as I am aware, all of such proposed mechanisms have been open to the objection that they require the application of considerable physical effort on the part of the operator to effect the shuttle changes, and furthermore, have failed to provide suitable means for placing fresh shuttles in position to be acted upon by the changing mechanism without interrupting the operation of the loom. Such prior mechanisms have also operated so that all the shuttles are changed at once.

45 One object of the present invention is to provide an improved shuttle changing mechanism for looms of the above described type by means of which the shuttles may be changed, either individually or collectively, 50 on any desired pick of the loom, and without interrupting the operation of the same, the power for operating the changing

mechanism being derived entirely from the movement of the lay. My improved mechanism also provides means for changing only 55 one half of all the shuttles on the loom at one time, thereby allowing the operator to divide his time between several looms to the best advantage. Other objects of my invention are to provide improved shuttle 60 holding devices which permit fresh shuttles to be positioned above the active shuttles while the loom is operating, and improved means for positioning the active shuttles with respect to the fresh shuttles prior to 65 the operation of the shuttle changing mechanism. These and other advantageous features of my invention will hereinafter more fully appear, reference being had to the accompanying drawings in which— 70

Fig. 4 is a plan view of a portion of the shuttle carrier shown in Fig. 1, with a shuttle in position therein.

Fig. 5 is a sectional view along the line 5, 5 in Fig. 4.

Fig. 6 is a view in rear elevation of a portion of my improved shuttle.

Fig. 7 is a view in rear elevation showing, on an enlarged scale, the device for positioning the shuttle carrier shown in Fig. 1.

Fig. 8 is a transverse sectional view along the line 8, 8 of Fig. 7.

Fig. 9 is a view in front elevation showing a portion of the breast beam of a loom, together with a number of the shuttle changing mechanisms shown in Fig. 1.

Fig. 10 is a transverse sectional view, on an enlarged scale, along the line 10, 10 in Fig. 9.

Fig. 11 is a diagrammatic view showing the mode of operation of the shuttle changing mechanism shown in Figs. 1, 2, 9 and 10.

Fig. 12 is a transverse sectional view, similar to Fig. 2, showing a modification of the shuttle changing mechanism.

Fig. 13 is a view partially in section and

partially in side elevation showing a portion of the parts of Fig. 12, on an enlarged scale.

Fig. 14 is a sectional view along the line 14, 14 in Fig. 12, looking in the direction 5 of the arrows.

Fig. 15 is a fragmentary sectional view showing the details of an arrangement for operating the shuttle changing mechanism shown in Fig. 12.

10 Fig. 16 is a plan view of the parts shown in Fig. 15.

Fig. 17 is an enlarged view in side elevation showing details of the parts shown in Fig. 15.

15 Figs. 18 and 19 are diagrammatic views illustrating the operation of the mechanism shown in Figs. 12, 15 and 16.

Fig. 20 is a sectional view of a portion of the parts of Fig. 12, showing a mechanism 20 for positioning the shuttle carrier.

Fig. 21 is a view in rear elevation of the parts shown in Fig. 20.

Like reference characters refer to like parts in the different figures.

25 Referring to Figs. 1 and 2 a portion of the lay of a loom is indicated at 1 and is provided with a slot 2 within which is located a toothed rack 3 that is adapted to be reciprocated back and forth by any suitable 30 means, not shown. A race block 4 is carried on the lay 1 above the rack 3 and a toothed pinion 5 is rotatably mounted at each end of the block 4 with its teeth in mesh with the teeth of the rack 3. A shuttle 35 carrier 6 is slidably mounted on the block 4 and is provided on its under side with teeth 7 which are in mesh with the teeth on the pinions 5, so that when the rack 3 is reciprocated on the lay 1 the shuttle carrier 6 will be moved back and forth on the race 40 block 4.

As best shown in Fig. 9 the blocks 4 are arranged at intervals along the lay 1 and each shuttle carrier 6 is of such length that 45 it will bridge the space between adjacent blocks 4 when moved by the rack 3. With this arrangement, the teeth 7 of the carriers 6 are always in mesh with either or both of the pinions 5 of the same block 4, or are in mesh with one pinion on each block when bridging the gap therebetween. The several 50 spaces between the blocks 4 are occupied by separate groups of warp threads 8 which are connected to the loom harness in the usual manner and so constitute the sheds through which the shuttle carriers 6 are to be moved back and forth. A shuttle holder block 9 is mounted on the lay 1 directly above every alternate race block 4 and a shuttle changing 55 mechanism is adapted to cooperate with each holder as will be hereinafter described.

Referring again to Figs. 1 and 2, each holder block 9 is provided with a holder 60 65 10 which, as best shown in Fig. 3 is formed of a strip of resilient material secured to the

block 9 by screws 10^a and bent outwardly at its ends to provide oppositely disposed U-shaped portions 11 that are somewhat yieldable. Each portion 11 is provided with a groove 12 that is adapted to receive the end 70 of a plate 13 mounted on the rear face of a shuttle 14. The shuttle 14 is provided with an opening 15 for receiving the filling carrier 16, the bow of the shuttle 14 being extended around the opening 15 in the usual manner to provide a handle 17 by means of which the shuttle may be seized and positioned in the holder 10 by forcing apart the portions 11. When the shuttle 14 is so positioned by the holder 10, it is held against movement in a plane at right angles to the lay 1. The shuttle 14 is, however, free to be moved downwardly between the portions 11 in the direction of the shuttle carrier 6 immediately below the block 9.

As best shown in Fig. 4 the carrier 6 is provided on its front face with a recess 18 within which is secured a strip 19 of suitable yielding frictional material, such as leather or fibre. The outer face of the strip 19 is substantially flush with the surfaces of the carrier 6 beyond the ends of the recess 18. A plate 20 is secured to the carrier 6 beyond the recess 18 and extends over the recess 18 as indicated at 21. Each end of the shuttle 14 is cut away as indicated at 22 to receive a projecting portion 21 of the plate 20 and the shuttle 14 is further provided on its rear face with a plate 23 which projects at each end into a cut away portion 22 of the shuttle. As best shown in Figs. 4, 5 and 6, the plate 23 is provided with serrations 24 and the edges of the plate are beveled as indicated at 25. The upper edge of the strip 19 is also beveled as indicated at 26, for a purpose to be hereinafter described.

As best shown in Fig. 2 a bracket 27 is mounted at the top of the lay 1 above each holder block 9 and provides a support for a 110 transferer 28, the normal position of which is directly above the shuttle 14 when positioned by the holder 10. Each transferer 28 is mounted on a spindle 29, surrounded by a spring 30, and terminating at its upper end in a head 31. A rocker arm 32 is pivotally supported between lugs 33 extending upwardly from the bracket 27, one end of the arm 32 resting on the head 31 of the transferer 28 and the other end being adapted to be engaged by a roller 34 carried on the upper end of a rod 35. The rod 35 is slidably mounted on the lay 1 in bearings 36 and its lower end is provided with a roller 37.

Referring to Figs. 1, 2 and 9, a plate 38 is secured to the bottom of the lay 1 and is provided with a dovetailed groove 39, within which is slidably mounted a plate 40. The plate 40 is provided with spaced dovetailed 130

grooves 41 within each of which is slidably mounted a bar 42, each bar being beveled at its end nearest the roller 37 as indicated at 42^a. The bars 42 extend below the breast beam 43 of the loom, a portion of which is indicated in Fig. 9, the other ends of the bars 42 terminating in a space between a pair of guides 44 extending longitudinally of the breast beam 43. As best shown in Fig. 10, a plurality of blocks are slidably mounted between the guides 44, the blocks being divided into groups of three, indicated at 45^a, 45^b and 45^c and each group of blocks being symmetrical about the axis of one of the transferrers. The middle block 45^b of each group is provided with a handle 46 by means of which the block may be moved between the guides 44. The right and left hand blocks 45^a and 45^c, respectively, of each group are connected to a rod 47 by means of links 48. The rod 47 is slidably mounted for longitudinal movement in bearings 49 secured to the lower guide 44 and is provided at its ends with handles 50 by means of which it may be shifted in the bearings 49 to move all of the blocks 45^a and 45^c in unison therewith.

As the lay 1 moves back and forth during the operation of the loom, the bars 42 will be carried therewith, and at the same time the plate 40 upon which the bars 42 are slidably mounted is moved back and forth in the slot 39 in the plate 38, by any suitable means, not shown. The means for moving the plate 40 is preferably coordinated with the means for moving the rack 3 so that the plate will move always in the same direction as the shuttle carriers 6. Inasmuch as the mechanism for moving the rack 3 is well known to those familiar with looms of this type, such mechanism will not be further described herein.

As the lay 1 moves back and forth, the above described movement of the plate 40 will cause the ends of the bars 42 to first enter the space between the left hand and center blocks 45^a and 45^b, respectively, on one forward beat of the lay and then enter the spaces between the right hand and center blocks 45^c and 45^b, respectively, on the next forward beat of the lay. As long as this movement of the bars 42 is uninterrupted, the parts will remain in the position shown in Figs. 2 and 11, and the transferrers 28 will remain inoperative. If, however, the middle block 45^b of any one group is moved to the right or to the left of its normal position into the path of movement of a bar 42 by means of the handle 46, the corresponding bar 42 will engage the block 45^b on the next beat on which the plate 40 is moved to the right or to the left as the case may be, whereupon the bar 42 will be moved away from the breast beam 43. This movement of the bar 42 causes the beveled end 42^a to be

forced under the roller 37 and to move the rod 35 upwardly, which movement of the rod 35 causes the rocker arm 32 to engage the head 31 of the transfer 28 and force it downwardly against the action of the spring 30. When this occurs, the transfer 28 engages that portion of the shuttle 14 directly beneath it and forces the shuttle downwardly out of the holder 10. The movement of the fresh shuttle 14 from the holder 10 is transmitted to the spent shuttle in the carrier 6 and the latter is ejected from the carrier. As the fresh shuttle moves downwardly, the lower beveled edge 25 of the plate 23 engages the beveled edge 26 of the strip 19, and as the downward movement continues, the shuttle 14 is forced bodily outward. As the ends of the plate 23 engage the projecting portions 21 of the plates 20, the latter are bent away from the carrier 6 and therefore tend to hold the serrations 24 of the plate 23 in close engagement with the strip 19. This frictional contact between the strip 19 and the many teeth 24 serves to hold the shuttle firmly in position on the carrier following its transfer from the holder 10 by the transfer 28.

From the foregoing, it is apparent that a fresh shuttle may be transferred from a holder to a carrier and an exhausted shuttle ejected at any time during the operation of the loom by moving any one of the middle blocks 45^b of any set into the path of movement of a bar 42. The operator may determine in advance, the pick on which the transfer is to occur by moving the block to the right or to the left, as desired. When a block 45^b is moved to the right the transfer occurs on the right hand pick and vice versa. In case it is desired to transfer fresh shuttles from all of the holders 10 at the same time, it is only necessary to move the rod 47, by means of the handle 50 far enough to the right, or to the left, to cause all of the blocks 45^a and 45^c, carried thereby, to engage all of the bars 42 upon the next forward beat of the lay, on which the plate 40 is moved to the right or to the left. This will cause all of the transfers 28 to be operated in unison to insert fresh shuttles into the carriers.

In order to insure that the carriers 6 are always properly positioned with respect to the holders 10, prior to the transfer of a fresh shuttle to a carrier, I have provided means for positively positioning each carrier 6 as it comes to rest after its movement to the right or to the left by the rack 3. This arrangement is illustrated in Fig. 7 which shows the rear of a carrier 6 and shuttle holder block 9 on an enlarged scale. A dumbbell-shaped locking member 51 is secured to the back of the carrier 6 by screws 52, the upper and lower surfaces 53 of which are adapted to be engaged by rollers 54 car-

ried at the ends of resilient arms 55. The arms 55 are secured to a block 56 on the lay 1 by plates 57 and screws 58 and tend to press the rollers 54 into close engagement 5 with the member 51 so that when the carrier 6 is moved to the right or to the left of the position shown, the rollers 54 are forced apart and the arms 55 are placed under considerable tension. As the carrier 6 returns 10 to its normal position, the rollers 54 press closely on the surfaces 53 of the member 51 and tend to always return the carrier to the same position at the end of its movement by the rack 3. In this way, the carriers 6 15 are always adapted to come to rest at substantially the same point beneath the holders 10 so that when a fresh shuttle is ejected from a holder 10 it will be properly received by the carrier 6. This positive positioning of the carriers 6 eliminates any 20 possibility of the shuttles jamming, owing to the failure of a carrier to be properly aligned with respect to a holder.

Referring to Figs. 12 to 20 inclusive, 25 there is shown a modification of the mechanism for transferring a shuttle from a holder to a carrier. Referring to Fig. 12, it will be seen that the arrangement of the carrier 6 and the holder block 9 on the lay 1 is substantially the same as described with 30 reference to Fig. 2. A transerrer 59 is mounted on a bracket 60 overhanging the block 9 and secured to the upper end of a rod 61. The rod 61 is slidably mounted in a 35 bearing 62 carried by the lay 1 and is surrounded by a spring 63 which tends to force the rod 61 upwardly and thereby hold the ejector 59 out of engagement with the holder block 9.

40 As best shown in Fig. 13 the lower end of the rod 61 is threaded to receive a hollow cylindrical sleeve 64. A second rod 65 is received in the lower portion of the sleeve 64 and its upper end is provided with a 45 pin 66 projecting at its ends into a slot 67 provided in the sleeve 64. The lower end of the sleeve 64 terminates in a flange 68 and the sleeve 64 is surrounded by a spring 69 extending between the flange 68 and the 50 pin 66. The spring 69 tends to hold the pin 66 in engagement with the top of the slot 67, so that the rods 61 and 65 are, under normal conditions, coupled together and are adapted to act as one member.

55 Referring to Figs. 12 and 14, the rod 65 is slidably supported in a bearing 70 secured to the lay 1, and terminates at its lower end in a squared head portion 71. A pin 72 extends through the portion 71 and has 60 mounted thereon rollers 73. A bell crank lever 74 pivotally mounted on a shaft 75 has one arm thereof terminating in a yoke portion 76 which embraces the rod 65 and rests upon the rollers 73. The end of the 65 other arm of the lever 74 is provided with

a seat 77 which receives a knob 78 provided at one end of a rod 79, slidably mounted on the lay 1 in a bushing 80. The other end of the rod 79 terminates in a head 81 and a spring 82 surrounds that portion of the rod 79 between the bushing 80 and the head 81. It is to be understood that a separate transerrer 59, together with an actuating mechanism as just described, is provided for each of the shuttle holders 10, above 75 every alternate carrier 6.

Referring now to Figs. 15 to 17 inclusive, a shaft 83 extends below the breast beam 43 and has mounted thereon a plurality of disks 84 which are spaced apart on the shaft 83 by substantially the same distance that separates the heads 81. Each disk 84 is secured to the shaft 83 by means of a key 85 which is received in a slot 86 provided on the shaft 83. Sleeves 87 are provided on 80 each side of the disk 84 and a flange 88, provided at the end of each sleeve, is held in engagement with the disk 84 by means of a spring 89 surrounding the shaft 83 between a collar 90 and a flange 91, provided at the outer end of each sleeve 87. In this way each disk 84 is normally held in 85 position midway between each pair of collars 90, each disk 84 being adapted to turn with the shaft 83 and being capable of sliding movement thereon against the action of the springs 89.

The shaft 83 is adapted to be given a reciprocal movement by any suitable 90 means, such for example, as a bell crank lever 92 which is adapted to be oscillated by means of a cam 93 mounted on a rotating shaft 94, although it is obvious that reciprocal movement may be imparted to the shaft 83 in any other suitable manner. The movement of the shaft 83 is so timed that with the several disks 84 in their normal positions, that is, midway between the collars 90, the shaft 83 may be moved from the position shown in Fig. 18 to the position shown in Fig. 19, while the lay 1 is making one beat, one backward and one forward. In other words, when the lay 1 makes its backward beat and moves the heads 81 to the position shown in dotted lines in Fig. 18, the shaft 83 is moved to the right into the position shown in Fig. 19, so that when the lay 1 makes its forward beat and the heads 81 return to the full line position of Fig. 19, the disks 84 will then be on the right hand side of the respective heads 81. It is obvious that this movement will continue without interference between the heads 81 and the disks 84 so long as the disks 84 are held centered by the springs 89, and the shuttle changing mechanism will remain inoperative.

In order to separately operate any one of the shuttle changing mechanisms, I provide 120 a pair of pins 95 mounted on opposite sides 125

of a supporting member 96, extending downwardly from the breast beam 43 in substantial alinement with a disk 84. Each pin 95 is normally held out of the path of movement of the disk 84, as the latter is moved back and forth with the shaft 83 by means of a spring 97 surrounding the pin between a lug 98 and an operating knob 99. Assuming that the disks 84 occupy the position shown in Fig. 18, that is, with each disk 84 to the left of its corresponding head 81, it is obvious that if a right hand knob 99 is depressed, the end of the pin 95 will project into the path of movement of its corresponding disk 84 when the shaft 83 is next moved to the right. Consequently, when the disk 84 engages the pin 95, further movement of the disk 84 will be prevented and the disk 84 will be held in the path of movement of the approaching head 81 on the next forward beat of the lay. It is obvious that this relative movement between the disk 84 and the shaft 83 will be permitted by the yielding of the left hand spring 89 on the shaft 83. When the head 81 engages the disk 84, as the lay completes its forward beat, the rod 79 will be forced into the lay 1, thereby turning the lever 74 in a clockwise direction. This movement of the lever 74 causes a downward movement of the rod 65 which is in turn transmitted to the rod 61 through the spring 69 and the sleeve 64, thereby causing the transerrer 59 to engage the shuttle which is in the holder 10 and force it downwardly into the shuttle carrier 9, in the same manner as described with reference to Fig. 2. The flexible connection between the rods 61 and 65, provided by the spring 69 prevents the shock of the impact between the heads 81 and the disk 84 from being transmitted directly to the transerrer 59, so that the downward force exerted by the latter member is applied evenly to the shuttle. From the foregoing, it is apparent that by depressing any one of the knobs 99, the corresponding shuttle changing mechanism can be actuated, and that the operator can select the pick on which he desires to have the shuttle change occur. For instance, if he wants the change to occur on the right hand pick, he depresses the right hand knob 99 of the corresponding disk 84, and should he desire to have the change occur on the left hand pick, he depresses the left hand knob 99.

In order that all of the shuttle changing mechanisms may be actuated at once, I provide further means for simultaneously arresting the movement of all of the disks 84 in either direction of movement of the shaft 83. To this end, each disk 84 is provided with a notch 100 which is of sufficient peripheral width to permit the passage therethrough of a pair of fingers 101 and 102

when the disk 84 moves with the shaft 83. As best shown in Fig. 16, the fingers 101 and 102 are secured to opposite sides of the member 96 and are provided with downwardly projecting end portions which are 70 adapted to pass through the notch 100 as the disk 84 moves back and forth. When it is desired to actuate all of the shuttle changing mechanisms at once, it is only necessary for the operator to turn a handle 75 103, provided at the end of the shaft 83, through a small angle, in either a clockwise direction or counter clockwise direction, thereby turning all of the disks 84 with respect to the fingers 101 and 102. When the 80 disks 84 are so turned it is obvious that either the fingers 101 or the fingers 102 will no longer register with the notches 100, so that when the disks 84 are moved to the right or to the left with the shaft 83, one 85 set of fingers 101 or 102 will engage the edges of the disks 84 and hold them in such position that they will be engaged by all of the heads 81 on the next forward beat of the lay. It is obvious that when the 90 heads 81 engage the disks 84, all of the transerrers 59 will be operated in unison to cause one half of the shuttles to be changed. Here again, the operator may choose the pick on which to bring about 95 the shuttle changes, for if he turns the shaft 83 in a clockwise direction, the fingers 101 will engage the disks 84 on the right hand pick, while if he turns the shaft 83 in a counterclockwise direction, the fingers 102 100 will engage the disks 84 on the left hand pick.

Referring now to Figs. 20 and 21, there is shown on an enlarged scale a mechanism for limiting the downward movement of a shuttle as it is positioned in the shuttle carrier by the transerrer 59. A pair of stops, each comprising a head 104, and a shank 105, extending through the block 4, are normally held in an inoperative position by 105 means of springs 106 surrounding the shank 105. In this position the heads 104 are clear of the lower edge of the shuttle 14 which is positioned on the carrier 6. An actuating member 107 is pivotally mounted 110 at 108 on the lay 1 and is normally held in a slightly inclined position by the ends of the shanks 105 pressing against the same under the force exerted by the springs 106. The member 107 is provided with an upwardly extending portion 109 which is normally located in the path of movement of a pin 110 secured to the rod 61. When the rod 61 moves downwardly, causing the transerrer 59 to transfer a shuttle from the 115 holder 10 to the carrier 6, the pin 110 is adapted to engage the portion 109 of the actuating member 107 at the moment when the fresh shuttle is positioned in the carrier 120 125 6. The member 107 is thereupon turned 130

upon its pivot 108 to cause the heads 104 to be moved outwardly far enough to prevent further downward movement of the shuttle 14 after it has been completely seated 5 in the carrier 6. Upon the upward movement of the rod 61, following a shuttle change, the springs 106 will return the heads 104 and the actuating member 107 to the position shown in full lines in Fig. 20, so 10 that the heads 104 will not prevent the spent shuttle from being ejected upon the occurrence of the next shuttle change. It is apparent that the above described mechanism for limiting the downward movement of a 15 shuttle in the carrier 6, may be applied to either of the constructions shown in Fig. 2 or Fig. 12.

From the foregoing it is apparent that I have provided an improved shuttle changing 20 mechanism for narrow ware looms which is extremely effective in its operation, inasmuch as the force for causing the shuttle changes is derived directly from the movement of the lay. Furthermore, my 25 improved shuttle changing mechanism is entirely selective in its mode of operation, inasmuch as the operator can cause the actuation of any one of the individual shuttle changing mechanisms on either a right hand or a left hand pick, or he can cause the 30 simultaneous operation of all the shuttle changing mechanisms, also on either pick. In this way, the operator can cause one half of all the shuttles on the loom to be changed 35 on a right hand pick, at one time, and at some time later can cause the remainder of the shuttles to be changed on a left hand pick. The arrangement whereby only one half of the shuttles are changed at one time, 40 is believed to be particularly desirable from the stand point of loom operation, for it enables the weaver to operate among several looms to better advantage than if all of the shuttles were to be changed at one time. Obviously, only one half of the total 45 number of shuttles in the loom have to be replaced at one time, following a shuttle change, so that the operator is unlikely to be engaged with any one loom for any considerable length of time, and is thus able 50 to give his attention to the other looms in case of an emergency.

I have further provided an improved shuttle holder for use with each changing 55 mechanism, whereby it is possible for the operator to easily place fresh shuttles in the holders following shuttle changes and while the lay is moving. The shuttle positioning and holding means on the moving 60 carrier are also particularly effective, inasmuch as it firmly holds the shuttle in position while the carrier is operating, owing to the cooperation between the resilient plates and the frictional contact obtained 65 between the serrations on the back of the shut-

tle and the strip on the carrier. My improved means for limiting downward movement of the shuttle in the carrier when a fresh shuttle is inserted, is also believed to be particularly advantageous, inasmuch as 70 it prevents the newly inserted shuttles from getting out of position in the carrier and thereby interrupting the operation of the loom.

While I have shown my improved shuttle changing mechanism as being partly operated by hand, it is not so limited, but is capable of being rendered entirely automatic in its operation, without departing 75 from the spirit and scope of my invention. For example, means may be provided for automatically causing operation of all of the transmitters after the shuttles have made a predetermined number of picks, such an arrangement being fully shown and described 80 in my copending patent application, Serial No. 567,719, filed June 12, 1922. I desire therefore that only such limitations be imposed on my invention as may come within 85 the scope of the appended claims.

I claim—

1. In a shuttle changing mechanism for looms, the combination with a lay, and a shuttle holder containing a shuttle and a shuttle carrier mounted on said lay, of a transquirer adapted to move a shuttle from said holder to said carrier, and means operated by the movement of said lay for actuating said transquirer.

2. In a shuttle changing mechanism for looms, the combination with a lay, and a shuttle holder containing a shuttle and a shuttle carrier mounted on said lay, of a transquirer adapted to move a shuttle from said holder to said carrier, and an actuating member for said transquirer adapted to be operated by movement of the lay.

3. In a shuttle changing mechanism for looms, the combination with a lay, a plurality of shuttle holders containing shuttles and a plurality of shuttle carriers mounted on said lay and a plurality of transmitters, each adapted to move a shuttle from a holder to a carrier, of means for operating said transmitters, either separately or collectively.

4. In a shuttle changing mechanism for looms, the combination with a lay, a plurality of shuttle holders containing shuttles and a plurality of shuttle carriers mounted on said lay and a plurality of transmitters, each adapted to move a shuttle from a holder to a carrier, of means for operating said transmitters either separately or collectively on any desired pick of the loom.

5. In a shuttle changing mechanism for looms, the combination with a lay, a plurality of shuttle holders containing shuttles and a plurality of shuttle carriers mounted on said lay and a plurality of transmitters,

each adapted to move a shuttle from a holder to a carrier, of means operated by the movement of the lay for operating said transferrers either separately or collectively.

5 6. In a shuttle changing mechanism for looms, the combination with a lay, a plurality of shuttle holders containing shuttles and a plurality of shuttle carriers mounted on said lay and a plurality of transferrers, each adapted to move a shuttle from a holder to a carrier, of a plurality of actuating members for said transferrers, each movable with the lay and adapted to operate a transferrer upon encountering a 15 member fixed with respect to said lay.

7. In a shuttle changing mechanism for looms, the combination with a lay, a plurality of shuttle holders containing shuttles and a plurality of shuttle carriers mounted 20 on said lay and a plurality of transferrers, each adapted to move a shuttle from a holder to a carrier, of a plurality of actuating members for said transferrers, each moving with the lay and a plurality of members 25 fixed with respect to the lay and adapted to be selectively placed in the path of movement of said actuating members to operate said transferrers, either separately or collectively.

30 8. In a shuttle changing mechanism for looms, the combination with a lay, a shuttle holder containing a shuttle and a shuttle carrier mounted on said lay and a transferrer for moving a shuttle from said holder 35 to said carrier, of means for positively positioning said shuttle in said carrier.

9. In a shuttle changing mechanism for looms, the combination with a lay, a shuttle holder containing a shuttle and a shuttle carrier mounted on said lay and a transferrer 40 for moving a shuttle from said holder to said carrier, of means for positively limiting the downward movement of the shuttle in the carrier.

45 10. In a shuttle changing mechanism for looms, the combination with a lay, a shuttle holder containing a shuttle and a shuttle carrier mounted on said lay and a transferrer for moving a shuttle from said holder to 50 said carrier, of means for automatically interposing a stop below said carrier for limiting the downward movement of the shuttle therein.

55 11. In a shuttle changing mechanism for looms, the combination with a lay, a shuttle holder containing a shuttle and a shuttle carrier mounted on said lay and a transferrer for moving a shuttle from said holder to 60 said carrier, of means for automatically placing a stop below said carrier before the shuttle reaches the end of its downward movement by the transferrer.

65 12. In a shuttle changing mechanism for looms, the combination with a lay and a shuttle holder containing a shuttle and a

shuttle carrier mounted on said lay, of a transferrer adapted to move a shuttle from said holder to said carrier, an actuating member for said transferrer adapted to be operated by movement of the lay, and a 70 yielding connection between said transferrer and said actuating member.

13. In a shuttle changing mechanism for looms, the combination with a lay and a shuttle holder containing a shuttle and a 75 shuttle carrier mounted on said lay, of a transferrer adapted to move a shuttle from said holder to said carrier, an actuating member for said transferrer carried by said lay and adapted to be operated by its engagement with a rigid member and a yielding connection between said transferrer and said actuating member.

14. In a shuttle changing mechanism for looms, the combination with a lay provided 80 with a movable shuttle carrier and a stationary shuttle holder, of a shuttle provided at its ends with projecting portions adapted to coat with said holder and on its back with a plate extending longitudinally thereof and adapted to be in frictional engagement with said carrier.

15. In a shuttle changing mechanism for looms, the combination with a lay provided 85 with a plurality of shuttle carriers containing shuttles and a plurality of shuttle transferring mechanisms, of means for selectively actuating said mechanisms separately, or for actuating said mechanisms, in unison, 90 to cause the changing of a predetermined number of the shuttles carried by the lay.

16. In a shuttle changing mechanism for looms, the combination with a lay provided 95 with a plurality of shuttle carriers containing shuttles and a plurality of shuttle transferring mechanisms, of means for separately actuating said mechanisms on any desired pick of the loom and for actuating said mechanisms in unison on either pick to 100 cause the changing of a predetermined number of the shuttles carried by the lay.

17. In a shuttle changing mechanism for looms, a lay, a relatively stationary shuttle holder carried by said lay, said holder comprising a piece of flat metal bent into U 105 shaped form with notches for the reception of projecting portions of a shuttle.

18. In a shuttle changing mechanism for looms, a lay, a race block on said lay, a shuttle holder attached to said race block 110 comprising a piece of flat metal, the end portions being first turned substantially at right angles to the body portion thereof and then doubled over towards each other, and notches in said doubled over portion for 115 the reception of a shuttle.

19. In a shuttle changing mechanism for looms, a lay, a race block on said lay, a shuttle holder attached to said race block, 120 said shuttle holder being made of spring 125

material and being provided with notches for the reception of the ends of plates disposed at the extremities of a shuttle.

20. In a shuttle changing mechanism for 5 looms, a lay, a race block on said lay, a shuttle holder attached to said race block, said shuttle holder being made of spring material and being provided with vertical notches for the reception of sharpened plates 10 disposed at the extremities of a shuttle.

21. In a shuttle changing mechanism for 15 looms, a lay, a race block on said lay, a shuttle holder attached to said race block,

said shuttle holder being made of spring material and being provided with vertical notches for the reception of sharpened plates disposed at the extremities of a shuttle, and said shuttle holder being adapted to resist the withdrawal of a shuttle in a horizontal direction, but allowing it to be forced down 20 in a vertical direction.

Dated this 23rd day of September, 1921.
GEORGE CROMPTON, JR.
